UNITED STATES PATENT OFFICE.

WILLIAM H. VAN SHRUM, OF COLUMBUS, OHIO.

DESIGN FOR A FLYING TOY.

55,732.

Specification for Design.

Patented July 6, 1920.

Application filed September 15, 1919. Serial No. 324,032. Term of patent 3½ years.

To all whom it may concern:

Be it known that I, WILLIAM H. VAN SHRUM, a citizen of the United States, residing at Columbus, in the county of Franklin and State of Ohio, have invented a new, original, and ornamental Design for Flying Toys, of which the following is a specification, reference being had to the accompanying drawing, forming part thereof.

The figure is a perspective view of a flying toy showing my new design.

I claim:

The ornamental design for a flying toy as shown.

WILLIAM H. VAN SHRUM.
